UNITED STATES PATENT OFFICE

2,545,085

CYCLE LIGHT SWITCH

Le Roy R. Hardy, Alvin, Tex.

Application July 22, 1949, Serial No. 106,162

1 Claim. (Cl. 200—24)

1

The principal object of the present invention is the provision of an improved means and of an improved method for producing distinct and, at the same time, uniform lighting effects over a maximum of area, using a minimum of light, so that a display sign using these means and methods will not appear garish.

Another object of the invention relates to improvements in devices and methods whereby a group of electric lamps can be lighted selectively at predetermined intervals.

A further object of the invention is to provide novel means for widely dispersing light from suitable electric lamps or the like over a maximum of area by means of centrally located actuation mechanism. The invention is to provide means for selectively lighting electric lamps and cutting them off at speeds faster than the human eye is sensitive to.

These, together with various ancillary features and objects of the invention which will later become apparent as the following description proceeds, are attained by this device, a preferred embodiment of which has been illustrated by way of example only in the accompanying drawings, wherein:

Figure 1 is a top plan view showing a preferred embodiment for carrying out the principles of this invention.

Figure 2 is a vertical sectional view taken substantially along the plane of line 2—2 of Figure 1.

Figure 3 is a fragmentary horizontal sectional view taken substantially along the line 3—3 in Figure 2.

Figure 4 is a fragmentary top view, taken upon an enlarged scale, of the arrangement shown in Figure 1.

Figure 5 is a diagrammatic view showing the relationship of the various circuits of this invention.

Referring now more specifically to the accompanying drawings, wherein like numerals designate similar parts throughout the various views, the numeral 10 designates generally the improved actuation device of the present invention. This actuation device 10 consists of a stationary outer member 12 having cylindrical side walls 14 and having a bottom 16 having an aperture therein for a purpose to be later described. This cylindrical stationary member is preferably made from an insulating material, but obviously could be made from such materials as desired. Inlaid in said stationary member along the side walls 14 thereof are a series of contact points which

are insulated from each other by plastic insulators 20 inlaid between each of said inlaid contacts 18.

At predetermined locations, the bottom of the stationary member 12 is thickened to form spacing means 22 and a central annular rim 24 surrounding the aforesaid aperture. Supported within a recess 26 of the annular rim 24 and secured to the spacing means 22 is a cover ring 28. The cover ring 28 thus provides a space 30 for wiring circuits which will be more fully described in ensuing portions of the specification. Within the aforesaid aperture in the stationary member 12 is a ball bearing encircled shaft 32 extending well above the cover ring 28 and rotatable within a sleeve 34 having flanges 36 secured to the rim 24 of the stationary member 12. Further, at suitable locations, commutating members 38 are rigidly secured to the bottom of the stationary member and extend through the cover ring 28.

An inner disk or wheel 40 is rigidly secured to the shaft 32 by such means as the bolt 42 and is rotatable within the outer stationary member 12. An inner annular recess 44 is provided in the bottom of the inner revolving disk or wheel 40. On the upper side of the annular recess 44 is an electrical contact plate 46. The commutating members 38 contact the contact plate 46 which is secured to the upper surface of the annular recess 44 as the inner revolving wheel is rotated. Electrically connected to the contact plate 46 are commutator brushes 48 which extend at desired intervals through the periphery of the inner revolving disk 40. These commutator brushes 48 are forced by spring means 50 to successively engage the contact points 18 on said stationary member 12. A motor 52 is secured to the under side of the bottom 16 of the stationary member 12 and, by pulley means 54, rotates the shaft 32 which, in turn, revolves the wheel 40.

Within the space for wiring 30 are situated the circuits connecting the contact points 18 in the desired manner. In the preferred embodiment 45 of the present invention, as can be seen more clearly in Figures 3 and 5, a source of power is connected to one terminal of the line 58 which then is connected to the commutating members 38, which, in turn, is connected to the contact plate 46. Electrically connected to the contact plate 46 are the commutating brushes 48. One end of element 60 is connected to the other terminal of the power source. Electric lamps 56 are connected to wires 62, one terminal of said wires 55 being connected in parallel to element 60, the

other ends of said wires being connected to a contact point 18. Thus, it is easily understood that as the inner disk revolves, it makes and breaks an electric circuit by the commutating brushes making and breaking contact with the contact points 18 in successive order. Thus, the circuits including the electric lamps 56 are intimately made and each lamp 56 is then alternately lighted.

Since the human eye will record anything blinking less than sixteen times a second, it is intended to alternately light the bulbs much faster by simply rotating the speed of the inner revolving disk 40 so that the electric lamps will be alternately lighted at a rate which the human eye is insensitive to. An example of the same motion would be a motion picture, where all the pictures are individual, yet one sees continuous motion without any unpleasant effect whatsoever. Thus, the electric lamps are turned on in such rapid succession that less than one-sixteenth of a second elapses between the lighting of each lamp in a complete cycle of the inner revolving disk 40. The advantage of the invention, therefore, is that a shop, factory, restaurant, or the like, using this device as an advertising means would produce the impression of lighting a window by means of a large number of lamps, while, in fact, it produces only the amount of light that would be produced by a fewer number of lamps. Thus, the illumination would be satisfactory for advertising displays that would not be garish, nor hurt the eyes as many present advertising signs do. The impression of the customer would be that of an elaborate decoration, since the illumination would be distributed over a greater predetermined area.

From the foregoing, the principles, operation and advantages of the invention will be readily understood, and accordingly further explanation is believed to be unnecessary. However, since numerous modifications and equivalents, falling within the spirit of the invention, will be readily understood by those skilled in the art after a consideration of the foregoing specification and annexed drawings, it is not intended to limit the

invention to the exact construction shown and described, but all suitable modifications and equivalents may be resorted to falling within the scope of the appended claim.

5 Having described the invention, what is claimed as new is:

- For use in an electric display system a device comprising a stationary cylinder having a cylindrical side wall and a bottom wall secured to said 10 cylindrical side wall, a plurality of spaced insulated contact points inlaid in said side wall, said bottom wall having spaced thickened portions forming spacing means, said bottom wall having a central aperture therethrough, an annular rim about said aperture, a cover ring supported by said rim secured to said spacing means, a shaft journaled in said bottom wall and extending through said aperture, commutating members secured to said bottom wall extending through 15 said cover ring, an inner disk rigidly secured to said shaft, an inner annular recess in the under-surface of said disk, a contact plate in said recess, said contact plate being engaged by said commutator members, a plurality of spaced commutator brushes secured to said disk, said commutator brushes being electrically connected to said contact plate, said commutator brushes successively engaging said contact points upon rotation of said shaft.
